UNITED STATES PATENT OFFICE.

CROMWELL O. RICHEY, OF AURORA, INDIANA.

IMPROVEMENT IN BRACES FOR BITS.

Specification forming part of Letters Patent No. 55,364, dated June 5, 1866; antedated May 16, 1866.

To all whom it may concern:

Be it known that I, CROMWELL O. RICHEY, of Aurora, Dearborn county, and State of Indiana, have invented a new and useful Improvement in Brace-Fastenings for Bits, of which the following is a full and clear description thereof, reference being had to the accompanying drawings, forming part of this specification.

My improvement embodies a new device by means of which a bit may be firmly secured in or readily removed from the brace.

Figure 1 represents a brace and bit with my improvement attached. Fig. 2 is an enlarged view of the neck of a brace and shank of a bit, the bit being removed from the brace. Fig. 3 is a perspective view of the neck of a brace as seen from beneath, showing several features of my improvement. Fig. 4 is a perspective view of a notched retaining-bar, which forms a part of my improvement.

A is the body of a brace. B is a bit, from the shank of which projects the pin b. C is a slot in the neck of bit A, which does not penetrate through to the cavity of the neck till near its lower end at the point c. A short distance from the extreme end of the neck of the brace is the recess c'', which opens into slot C, and is for the purpose of admitting the pin b. D is a retaining-bar playing in slot C. The upper end of the retaining-bar D has a cylindrical projection, d, which passes through the upper part of neck D, and is pressed upon by spring E, which is secured to the brace. A projection from the back part of the retaining-bar at e is of equal depth to thickness of the bridge

of slot C, as shown at point e. f and g are offsets from the front part of the retaining-bar, and check its motion in opposite directions. c' is a depression in the neck D, which receives the ferrule k.

Operation: Introduce the shank of the bit into the cavity in the neck of the brace in such a manner that the pin b shall pass up the slot C, the retaining-bar D having been drawn up to a sufficient height as will enable the pin b to enter the recess c'' at the time the bit is rotated. The hand is then removed from the knob h upon retaining-bar D, when the spring E forces down the bar D so that the extreme end shall fill that part of slot C beneath the ferrule k, thus effectually securing the bit B to the brace A. In liberating the bit draw upon the retaining-bar D, pressing back the spring E until the offset g comes in contact with point e. The bit B may then be rotated until the pin b is passed into slot C, when the bit may be withdrawn.

The simplicity of this operation economizes much in the use of the tool.

Having described the construction of my improved brace-fastening for bits and the use of its various parts, I make the following claim:

The retaining-bar D, spring E, ferrule k, and slot C, in combination with bit B and pin b, arranged as above described, and for the purpose set forth.

CROMWELL O. RICHEY.
